INVENTOR,

Thomas J. Flagg
By David A. Burr, Atty.

UNITED STATES PATENT OFFICE.

THOMAS J. FLAGG, OF NEW YORK, N. Y., ASSIGNOR TO FISK, CLARK & FLAGG, OF SAME PLACE.

NECKSCARF.

SPECIFICATION forming part of Letters Patent No. 237,006, dated January 25, 1881.

Application filed November 9, 1880. (No model.)

To all whom it may concern:

Be it known that I, THOMAS J. FLAGG, a citizen of the United States, and a resident of the city, county, and State of New York, have 5 invented certain new and useful Improvements in Neckscars; and I do hereby declare that the following is a full, clear, and exact description thereof, reference being had to the accompanying drawings, and to the letters of 10 reference marked thereon, making a part of this specification.

This invention relates to the shield or stiffening-piece for made-up neck scarfs and ties. It has for its object the production of a neater 15 fit and better form for the scarf or tie upon the neck; and it consists in forming one or more joints or flexible lines in the shield or stiffening-piece, so that while affording firm support in one direction the shield will freely yield in 20 another.

In the accompanying drawings, Figure 1 is a view of the reverse or under side of a scarf fitted with my improved shield constructed in two sections, Fig. 2 being a front elevation of 25 the same scarf. Fig. 3 is a cross-section of a detached shield upon an enlarged scale, illustrating one mode of constructing the same, Fig. 4 being a similar view of a shield whose sections are hinged together by its lining or 30 covering-piece. Fig. 5 illustrates my improved shield constructed with a plurality of sections, defined by indentations in the material composing it, and applied to a wide form of made-up scarf.

The improved shield may be formed by cutting up an ordinary shield of prepared card-board or other suitable material into two or more sections, and then uniting these sections by flexible strips which form hinged joints, 40 or by perforating, indenting, or otherwise reducing the thickness or stiffness of the material in lines which shall serve to separate the several sections and form a joint or hinged connection between them. The sections are ordinarily arranged to extend parallel to the length 45 of the scarf, so that the scarf, although stiffened and supported vertically by the flexible shield, is free to yield laterally and conform to the neck.

In the drawings, A A represent the scarf;

B, the sectional or flexible shield; D, the neck-band, engaging the shield at or near its upper corners.

The shield B, Fig. 1, is composed simply of two sections, *cc*, which, being jointed together, 55 will constitute a stiffening-piece adapted to the scarf A. The sections *cc* are made of water-proof pasteboard, thin metal, or other material commonly used for this purpose. They are preferably lined or covered with a 60 suitable lining fabric, which, in such case, may be carried in one piece over both sections, so that when stitched or otherwise secured thereto it will itself form the hinge between them, as shown in Fig. 4, or they may be separately 65 lined or finished without lining, and be hinged together by a distinct strip, *e*, Fig. 3, covering the joint; or the shield may be constructed of one piece of material separated into sections by one or more indented lines constituting the 70 necessary flexible joints, as shown in Fig. 5.

The jointed shield B, when made in two sections, is especially adapted for narrow scarfs constructed in imitation of a tie, the joint or line of flexion in the shield producing a slight 75 fold in the upper end of the scarf, when it is drawn and secured by the neck-band, (see Fig. 2,) which causes it to resemble the more closely a tied scarf, and relieves its upper edge of the stiffness ordinarily found in such made-up 80 scarfs.

A recess, *f*, is formed centrally at the upper end of the shield by cutting away, slightly, the corners of its two sections to receive and embrace the collar-button of the wearer, and the 85 tie is thereby prevented from riding up upon the collar or moving from side to side.

For wider scarfs, and especially flat scarfs of all descriptions, it is advisable to divide the shield into several sections, which, being 90 united together by flexible joints, constitute a single flexible shield, as shown in Fig. 5.

It is evident that my invention is adapted to shields of all shapes and sizes, and I contemplate its use with any and all descriptions 95 of made-up scarfs.

Various methods of producing a flexible joint between the sections of the shield suggest themselves—as, for instance, by perforating or scoring the material thereof, or otherwise re- 100

ducing its stiffness or thickness in lines which will then serve to separate the sections and form the desired flexible joint between them, and I contemplate all known methods of producing a hinged or flexible connection between the divisions of the shield, as well as the use of any suitable material in its manufacture.

I am aware that scarf tops or headings have been constructed of pasteboard or its equivalent, with side flaps to be folded inward, in the construction of a scarf therewith; but these flaps are fastened in a fixed position after being folded, the shield or stiffening piece remaining inflexible in the finished scarf. My invention contemplates a jointed or hinged shield or heading for the scarf which shall yield and bend at the joint whenever it is adjusted upon the neck of the wearer.

I claim as my invention—

1. A shield or stiffening-piece for neck ties and scarfs, provided with one or more joints or creases therein, formed and adapted to permit

a play or flexion of the shield when in use, substantially as and for the purpose herein set forth. 25

2. The combination, in a single shield or stiffening-piece for made-up neck ties and scarfs, of independent sections hinged or jointed together by a flexible connection, substantially as and for the purpose herein set forth. 30

3. The combination, with a made-up scarf, and with its neckband, of a shield or stiffening-piece made flexible by one or more joints therein, and adapted to be conformed to the neck of the wearer by means of the neckband, substantially as and for the purpose herein set forth. 35

In testimony whereof I have signed my name to this specification in the presence of two subscribing witnesses.

THOS. J. FLAGG.
